UNITED STATES PATENT OFFICE.

EDWARD H. WISTANCE, OF SPRINGFIELD, OHIO.

FERTILIZER-DISTRIBUTER.

SPECIFICATION forming part of Letters Patent No. 286,361, dated October 9, 1883.

Application filed July 2, 1883. (No model.)

To all whom it may concern:

Be it known that I, EDWD. H. WISTANCE, of Springfield, county of Clarke, and State of Ohio, have invented a new and useful Improvement in Fertilizer-Distributors, of which the following is a full, clear, and exact description, reference being had to the accompanying drawings, making a part of this specification.

My invention relates to an improvement in that class of fertilizer-distributors in which a revolving hopper is employed and the fertilizing material is fed through the bottom of said hopper into the tube or hollow tooth, which conveys it to the ground; and it consists in the combination, with a suitable frame, of a revolving hopper having within it, near its bottom, several adjustable plates or scrapers for acting upon the material contained in the hopper, and a stationary bottom to said hopper, provided with an opening and an adjustable gate for regulating the passage of the grain to the conducting-tube.

It also consists in a novel manner of adjusting the regulating-gate, and in certain other details of construction and arrangement hereinafter fully described.

In the accompanying drawings, Figure 1 is a plan view of my improved distributor, showing the arrangement of the scrapers, gate, gate-adjusting lever, driving-shaft, and also the manner of supporting the base-plate of the frame. Fig. 2 is a sectional view, showing the arrangement of gearing for driving the revolving hopper, and the lever and link for adjusting the gate of the discharge-outlet; and Fig. 3 is a perspective view of the revolving hopper, a portion of the casing removed to show the arrangement of the scrapers, their retaining-springs, and the interior frame, to which they are secured.

A represents the main frame of the hopper, and, as it may be of any suitable or desired form, need not be herein described any further than is necessary to explain its connection with other parts of the machine.

To the lower edges of two of the sides of frame A is attached the base-plate A' of the frame, of the form shown in Figs. 1 and 2—that is, it is provided with four legs or arms, A², which extend out beneath the lower edges of the two sides of the hopper above mentioned, and are secured thereto. Its central portion

is cylindrical in form, and is curved or projected up within or between the side walls of hopper A, the upper extremity of this curved projection having formed upon its inner periphery two or more lugs, a, as shown in Fig. 2, and for a purpose hereinafter explained. The base-plate A' has further formed upon its lower face a bracket, a', Fig. 2, containing a bearing, or, if preferred, forming in itself a bearing for the driving-shaft of the machine.

B represents a revolving ring, having a central perforation of considerable size, said ring, when in motion, revolving around the cylindrical projection A', resting on the latter for a bearing, as shown at B', Fig. 2, being steadied in its movement or revolution by means of an annular flange or shoulder, B', which rests in contact, or nearly so, with the exterior face of the curved projection A'.

Resting upon the rotating circle B is the stationary bottom D of the hopper, which is held in place by means of bolts or screws attached thereto, and passing through and secured in the lugs a, above referred to. Thus it will be seen that the ledge or projection B' of ring B is interposed and revolves between the cylindrical formation of the base-plate and the stationary hopper-bottom when motion is imparted to it. Upon the under periphery of ring B are formed beveled teeth b, adapted to mesh with the teeth of bevel-gear wheel C, arranged at right angles thereto upon the main driving-shaft C' of the machine. The bevel-gear wheel is keyed to the driving-shaft C' and revolves with it, imparting motion to the ring B through its mesh with the bevel-gear formation upon the under side of said ring. An annular vertical flange, D', is formed around the outer periphery of the stationary hopper-bottom D, for containing within its walls the cylindrical hopper E, as shown in the drawings. The cylindrical hopper E is not attached in any way to the hopper-bottom, but revolves above the same, the only office of the annular flange D' being to confine the hopper within its walls and steady its movements. The cylindrical hopper is connected with the revolving ring B by means of angle-irons e, secured to the hopper by rivets, or in any suitable manner, and united to lugs b' on the ring B in a similar manner. Thus when the ring B is caused to rotate by means of gearing above re-

ferred to, said ring, through the aid of the angle-irons *c*, will rotate the hopper and its contained mechanism, which will now be explained. Within the said hopper, and extending vertically through its center is a shaft or rod, *F*, of any suitable diameter, and which has radiating from its upper extremity a series of arms, *ff*. (Shown most clearly in Fig. 3.) These arms extend out to and at their outer extremities are fastened or secured to the inner walls of the rotating cylindrical hopper, whereby they form part of the hopper, and when the latter is rotated they, together with the central shaft, *F*, are carried with it. The shaft or rod *F* has upon its lower end a shank or its equivalent, fitting into a formation, *D*, upon the stationary hopper-bottom, which serves as a bearing for the said shaft *F* when it is rotated.

20 G represent the scrapers contained within the hopper. They may be of any desired form or construction, that shown in the drawings being preferred, as being cheap and durable. These scrapers are hinged at their upper ends or edges between the central shaft, *F*, and the inner wall of the hopper by pins *g*, or in any preferred manner, their lower scraping-edges being always in contact with the stationary hopper-bottom, and inclining a little backward relatively to the direction in which they revolve. They are held in place and kept to their work by means of suitable springs, *g'*, secured in the radiating arms *ff* of the central shaft or rod, *F*, and extending down behind the said scrapers, exerting their tension upon the latter and keeping their lower scraping-edges always in contact with the floor.

25 H represents the opening in the bottom of the hopper, through which the material contained in the hopper is fed to the mouth of the tube or tooth, which afterward conveys it to the ground. This hole extends from the central shaft, *F*, to the inner wall of the cylindrical hopper, or thereabout, and at or near one of its edges is hinged a plate or gate, *I*, the purpose of which is to regulate the amount of fertilizer which shall be allowed to pass through the opening; and for the purpose of adjusting said gate with ease I provide the following means: The gate *I* is provided on its under side with a pendent loop or hook, *i*, for receiving a link or links, *i'*, which connect with a crank-arm, *K*, as shown 30 in Fig. 2, mounted upon a shaft, *L*, and se-

cured thereon by means of a set-screw, *l*, whereby when the shaft is rocked in its bearings, which are in the frame of the hopper, the crank will be moved with it and will open or close the gate *I* through the connecting-link *i'*, according to the direction in which the shaft *L* is rocked. The shaft *L* is rocked, for the purpose of increasing or decreasing the size of the opening *H*, by means of a hand-lever, *L'*, keyed or otherwise securely fastened upon the shaft *L*, said hand-lever being provided with a longitudinal tooth, *l'*, which is adapted to engage with or between a series of teeth formed within a slotted guide, *M*, secured to the frame of the machine, thus adapting the gate, when properly adjusted, to be held at such adjustment while the machine is in operation.

Having now described my invention, what I claim as new is—

1. In a fertilizer-distributer, the combination, with a revolving hopper, of a stationary bottom thereto, provided with an opening and means for increasing or diminishing the size of said opening.

2. The combination, with a revolving hopper, of a stationary bottom having an opening for the escape of the fertilizer, and a pivoted gate adapted by suitable mechanism to be rocked on its pivot, for the purpose and substantially as described.

3. The combination, with the hopper *E*, of the ring *B*, the interposed angle-irons connecting said hopper and ring, and means, substantially as described, for actuating said ring.

4. The combination, with the stationary bottom *D*, having the opening *H* and regulating-gate *I*, of the scrapers *G*, actuated in the manner and for the purpose substantially as described.

5. The combination, with the stationary bottom *D*, having the opening *H* for the escape of the material contained in the hopper, of the scrapers *G* and springs *g'*, operating substantially as described.

6. The combination, with the revolving hopper, of the frame-work *F* *ff*, the pivoted scrapers *G*, and springs *g'*, arranged and operating substantially as described.

In testimony whereof I have hereunto set my hand this 28th day of June, A. D. 1883.

EDWARD H. WISTANCE.
